UNITED STATES PATENT OFFICE.

JOHN McCLELLAND, OF KANSAS CITY, MISSOURI.

DESIGN FOR A FRAME FOR CLOSET-PARTITIONS.

46,883.

Specification for Design.

Patented Jan. 26, 1915.

Application filed May 28, 1914. Serial No. 841,661. Term of patent 7 years.

To all whom it may concern:

Be it known that I, JOHN McCLELLAND, a citizen of the United States, residing at Kansas City, in the county of Jackson and State of Missouri, have invented a new, original, and ornamental Design for a Frame for Closet-Partitions, of which the following is a specification, reference being had to the accompanying drawing, forming part thereof.

The figure is a perspective view of a closet partition, showing my new design.

I claim:

The ornamental design for a frame for closet partition, as shown.

JOHN McCLELLAND.

Witnesses:

LETA E. COATS,
LYNN O. ROBINSON.
